UNITED STATES PATENT OFFICE.

AUGUST LEIB, OF BERLIN, GERMANY, ASSIGNOR TO GESELLSCHAFT FUR DRAHTLOSE TELEGRAPHIE M. B. H., OF BERLIN, GERMANY, A CORPORATION OF GERMANY.

INDUCTANCE COIL.

Application filed April 29, 1924. Serial No. 709,818.

To all whom it may concern:

Be it known that I, AUGUST LEIB, a citizen of Germany, and residing at Berlin, Germany, have invented new and useful Improvements in an Inductance Coil, of which the following is a specification.

This invention relates to inductance coils such as are used in radio frequency work.

An object of the invention is to provide an inductance coil, more particularly a flat inductance coil, which is provided with an iron core and which shall have a high self-inductance and minimum iron losses.

This and other objects will be apparent from the following description when considered with the accompanying drawing in which—

Fig. 1 is a perspective view of the iron core partly wound into a spiral.

Fig. 2 is a plan view of the coil with the iron core completely wound into a spiral with the fingers bent to overlie the coil winding radially.

Fig. 3 is a view similar to Fig. 2 but additionally showing the coil winding surrounded by an outside iron band.

According to the present invention the induction coil may be of any size, proportions and dimensions. However, this invention is best adapted to be used with flat coils such as the pancake type, spider web type, etc. The most favourable dimensions of flat coils for radio frequency is fully discussed in a publication by Dr. A. Meissner entitled, "The construction of coils for radio frequency technics and their application," which publication may be found in the "Year Book for Wireless Telegraphy and Telephony" on page 57 and the following pages volume 3, book 1, year of 1909.

Referring to the drawing, the flat coil consists of winding S and an iron core B. The winding S may be surrounded by an iron band C.

The core B is made up of a strip of very

thin sheet iron rolled up into a cylindrical shaped spiral for the least iron losses. The outermost convolution of the spiral may have three adjoined side fingers A₁, A₂, A₃. After the core is wound into spiral form and inserted into the coil winding S the fingers A₁, A₂, A₃ may be bent down so that they rest and extend radially on the end of the coil winding S.

The coil may be provided with the outside iron band C, as in Fig. 3, for attaining the smallest possible reluctance for the magnetic circuit and in that case the fingers A₁, A₂, A₃ may be so dimensioned as to reach the band C and so close the magnetic circuit.

It will be obvious to those skilled in the art that the self-inductance of the coil can be controlled by the size, number and position of the fingers A₁, A₂, A₃.

It is also obvious that this invention is applicable to other kinds of induction apparatus, such as, for instance, transformers.

Having now described my invention, I claim:

1. An inductance coil, comprising a spiral, very thin, sheet iron core, a winding surrounding the said core, an iron band surrounding the said winding, the said core having very thin sheet iron fingers extending therefrom outwardly to the said band to close the magnetic circuit.

2. A coil comprising a spiral sheet iron core, a winding on said core, an iron band surrounding said winding and fingers integral with said core extending across the winding and joining said band to close the magnetic circuit.

3. A coil comprising a spiral sheet iron core, a winding on said core, an iron band surrounding said winding, sheet iron fingers extending from said core of sufficient length that they may be bent to approach said band to vary the reluctance of the magnetic circuit.

AUGUST LEIB.
